United States Patent

Des. 236,842
Patented Sept. 16, 1975

236,842

GYMNAStic EXERCISE APPARATUS

Kirk Z. Wilson, 919 Wilshire Blvd.,
Santa Monica, Calif. 90401

Filed Sept. 17, 1973, Ser. No. 397,582

Term of patent 14 years

Int. Cl. D21—02

U.S. Cl. D34—5 K

FIG. 1 is a perspective view of a gymnastic exercise apparatus showing my new design;

FIG. 2 is a side-elevational view thereof;

FIG. 3 is a top plan view thereof;

FIG. 4 is a front-elevational view thereof; and

FIG. 5 is a rear-elevational view thereof.

I claim:

The ornamental design for gymnastic exercise apparatus, as shown and described.
